UNITED STATES PATENT OFFICE.

FRANK LOCKETT, OF EAST LIVERPOOL, OHIO, ASSIGNOR TO THE LIMOGES CHINA COMPANY, OF SEBRING, OHIO, A CORPORATION OF OHIO.

DESIGN FOR A PITCHER.

48,597.

Specification for Design.

Patented Feb. 22, 1916.

Application filed December 14, 1915. Serial No. 66,856. Term of patent $3\frac{1}{2}$ years.

To all whom it may concern:

Be it known that I, FRANK LOCKETT, a citizen of the United States, residing at East Liverpool, in the county of Columbiana and State of Ohio, have invented a new, original, and ornamental Design for a Pitcher, of which the following is a specification, reference being had to the accompanying drawing, forming part thereof.

In the drawings: Figure 1 is a side elevation of the pitcher, embodying my new design. Fig. 2 is a top plan view of the pitcher.

I claim:

The ornamental design for a pitcher, substantially as shown.

FRANK LOCKETT.
